United States Patent Office.

BARNA T. STOWELL, OF QUINCY, ILLINOIS.

Design No. 4,517, dated December 13, 1870.

DESIGN FOR HOES.

The Schedule referred to in these Letters Patent and making part of the same.

To all whom it may concern:

Be it known that I, BARNA T. STOWELL, of Quincy, in the county of Adams and State of Illinois, have invented and produced a new and original Design for a Hoe; and I do hereby declare the following to be a full, clear, and exact description of the same, reference being had to the accompanying drawings making a part of this specification, in which—

Figure 1 is a perspective view, and

Figure 2 is a transverse longitudinal section.

This invention consists in a hoe shaped as hereinafter described, that is to say—

First, slightly curved crosswise, or from side to side, and curved to a greater degree lengthwise, or from end to end, so as to form a blade concave in both directions as to its inner surface or that next to the handle, and convex in both directions as to its outer surface.

Second, widest at its front end or cutting-edge, and with sides inclined slightly inward and backward from both front corners to points at one-third, more or less, the distance from the front to the rear, thence inclined

more rapidly inward, with a convex curvature, till the hoe is narrowed to one-third, more or less, of the width of its front edge, and thence running in converging directions to the rear end of the hoe, forming a narrow prong behind the handle.

Referring to the drawings—

a is the cutting-edge of the blade;

b b, its inclined sides;

c, the rear prong; and

d, the inclinations connecting the sides *b* with the sides of the prong.

Having thus described my invention,

What I claim as new, and desire to secure by Letters Patent, is—

The design for a hoe, as herein shown.

To the above specification of my invention I have signed my hand this 4th day of November, A. D. 1870.

BARNA T. STOWELL.

Witnesses:

GEORGE N. MILLS,
JAS. J. LANGDON.
